(57) **CLAIM**

What is claimed is the ornamental design for a compression tool, as shown and described.

DESCRIPTION

FIG. 1 is a perspective view of a compression tool showing the new design;

FIG. 2 is a left side elevational view thereof;

FIG. 3 is a right side elevational view thereof;

FIG. 4 is a top plan view thereof;

FIG. 5 is a bottom plan view thereof;

FIG. 6 is a rear side elevational view thereof; and,

FIG. 7 is a front side elevational view thereof.

The elements shown in dotted lines are provided for illustrative purposes only and form no part of the design claimed.
